UNITED STATES PATENT OFFICE

ANTHONY F. G. LUCAS, OF WASHINGTON, DISTRICT OF COLUMBIA

DESIGN FOR A TABLE

Application filed December 8, 1930. Serial No. 37,919. Term of patent 14 years.

To all whom it may concern:

Be it known, that I, ANTHONY F. G. LUCAS, a citizen of the United States, residing at Washington, in the District of Columbia, have invented a new, original, and ornamental Design for Table, of which the following is a specification, reference being had to the accompanying drawings, forming part thereof.

Fig. 1 is a side view of the table showing my new design.

Fig. 2 is an end view thereof.

I claim:

The ornamental design for a table as shown.

ANTHONY F. G. LUCAS.
